RUG AND PILE FABRIC MANUFACTURE

Basilia Spesso, Turin, Italy

Application April 27, 1934, Serial No. 722,609
In Italy May 6, 1933

3 Claims. (Cl. 112—1)

This invention relates to a process for the manufacture of rugs, carpets and pile fabrics without the use of a loom and to a device for carrying out said process. According to this invention in the manufacture of a rug, carpet or pile fabric a rod is used which is held against a canvas, and about which is passed the needle carrying a plurality of threads, e. g. wool threads in various colours threaded therein. The work is carried out as if the rod were to be sewn to the canvas, without, however, tightening the successive loops thus formed. The rod is then slipped off leaving a tube formed by the successive loops of thread. This tube is cut forming the pile which is fixed to the canvas by machine-sewn stitches. These stitches can be sewn, after cutting the tube, between the two pile rows, or they can be sewn before cutting the tube laterally of and at the root of the loops. It is preferable to sew two rows of stitches to fix the pile safely.

In carrying out this process it has been found that the work can be much expedited by employing a rod of a much larger section than would be necessary to obtain the desired pile height; it is thus possible, once the tube of large-sized successive loops has been formed, to sew by means of the sewing machine at least one middle row of stitches thus forming two rows of loops of the suitable size to obtain the desired pile height, these stitches fixing at the same time the pile. The two tubular rows of loops thus formed and fixed are cut and the same result is obtained which necessitated two operations with the former process.

Consequently, by employing a rod of such size as to allow of two intermediate rows of stitches enabling the formation of three tubular rows of loops, the work obtained from one row of loops is three times as much as compared with the first mentioned process, and so on, as the number of rows of machine stitches increases.

The process according to this invention is carried out rapidly and efficiently by means of a device consisting of two rods which can be united to form a fork provided with a handle at one end, these rods being introduced into the large-sized loop tube as soon as it is formed, whereupon they are spread apart by means of a suitable spacing member at their free end. The stitches are sewn on the sewing-machine in the space between the two rods which keep the large-sized loops flat and stretched. The needle is thus guided and the work proceeds rapidly and efficiently.

To facilitate the introduction of the fork a suitable pointed cap is fitted on the free ends of the rods and is removed when the fork has been placed in position for fitting the aforesaid spacing member on the free rod end.

The accompanying drawing shows by way of example and diagrammatically three modes of carrying out the process according to this invention and the devices therefor.

Figure 1 is a perspective view showing the process at the end of three successive stages, namely formation of the loops, having the required size for giving the desired pile height, cutting the loops lengthwise and sewing the central row of stitches.

Figure 2 shows also in a perspective view another mode of carrying out the process in which the row of stitches are sewn laterally of and at the root of the loops and the tube of loops can be cut before or after sewing the stitches.

Figure 3 shows the higher efficiency process in which one middle row of stitches forms from a large-sized loop tube made with the use of a large rod, two tubes of adjacent loops which are safely fixed to the canvas by the stitches, and are cut lengthwise to form the pile.

Figures 4 and 5 show the device employed in carrying out the process according to Figure 3 to stretch the tube of loops and guide the central row of stitches.

Figure 6 shows a modified form of the device.

Figure 7 is a view, similar to Figure 3, of a modification in which the loop tube is fixed to the base fabric by a plurality of parallel rows of stitches instead of by only one.

As shown in Figure 1, the work is executed by employing a canvas 1, a rod 11 of suitable size which is held against the canvas and a needle in the eye of which the yarn of the desired color is passed.

By means of the needle 12 successive loops 2 are formed about the rod 11 and through the canvas 1 and when the rod is removed a tube of loops is fixed to the canvas. This tube of loops is cut along the upper generatrix and opened and the tufts thus formed projecting from the canvas are fixed by a row of machine-sewn stitches 3 passing through the pile root. By employing successively threads of different colors for determined groups of loops any desired pattern can be obtained. The pile height depends upon the section of the rod 11 used.

In the modification shown in Figure 2, the row of stitches 31 are sewn laterally of and at the root

of the loop tube and the tube can be cut before or after sewing.

In the modification shown in Figure 3, a rod 11 of larger size is employed and a tube 4' of 5 larger loops is formed from which two adjacent tubes 4₁, 4₂ are obtained by sewing an intermediate row of stitches 5 on the loops. This row of stitches besides forming two tubes from one 10 larger-sized tube secures to the canvas the pile obtained by cutting the top of the two tubes of loops.

In another modification, shown in Figure 7, the loop tube is applied to the base fabric 1 in the manner described above, and is flattened 15 against said fabric and fixed thereto by means of two parallel rows of stitches 11 and 12, of which one is made on the row of loop roots. The tube is thereby subdivided into three regions 13, 14 and 15. The intermediate region 15 is cut along the 20 middle line between the rows of stitches 11 and 12 and the lateral regions 13 and 14 are cut along the free edge.

In sewing the middle row of stitches I preferably make use of a fork consisting (Figures 5 and 25 6) of two rods 6 of which one end is connected by a handle 7 which facilitates the operation thereof, and the other end is free.

When the large-sized tube of loops has been 30 formed, a cap 1 shown in Figure 5 is fitted on the free ends of the fork. This cap draws together the free ends of the rods 6 of the fork and allows of a prompt and easy introduction of the latter into the tube of loops.

When the fork is fully introduced, the cap 7 is 35 removed and replaced by the spacing member 8 which spreads apart the rods 6 as shown in Fig. 4. It is thus possible to sew easily and rapidly the row of stitches to form the two tubes of loops.

40 Instead of the fork shown in Figures 4 and 5, I may employ the device shown in Figure 6 consisting of two independent rods 6₁ which may be superposed to allow of an easy introduction into the tube of loops and, once they have been

introduced, are kept in place at the necessary distance to flatten and stretch the loops by means of the spacing members 9 and 10.

What I claim is:

1. Process for the manufacture of carpets by 5 hand without the use of a loom, comprising applying against a base fabric a rod, forming about said rod a helical winding of pile thread, passing said pile thread at each turn through said base fabric, removing the rod from said winding, cutting the turns along a line midway between the lines at which the wound thread penetrates the base fabric, and fixing said turns to the base fabric by stitches along the root of the turns.

2. Process for the manufacture of carpets by 15 hand without the use of a loom, comprising applying against a base fabric a rod of which the cross section is of a peripheral length which is a multiple of the pile length, forming about said rod a continuous winding of pile thread, passing the 20 pile thread at each turn through the base fabric, removing the rod from said winding, flattening said winding against the base fabric, sewing a row of stitches along the middle line of the flattened winding, and cutting the two tubular portions thus formed along a line midway between the lines at which the wound thread penetrates the base fabric.

3. Process for the manufacture of carpets by 30 hand without the use of a loom, comprising applying against a base fabric a rod of which the cross section is of a peripheral length which is a multiple of the pile length, forming about said rod a continuous winding of pile thread, passing the 35 pile thread at each turn through the base fabric, removing the rod from said winding, flattening said winding against the base fabric, sewing a plurality of parallel longitudinal rows of stitches on said flattened winding to form a plurality of tubular portions side by side and cutting said 40 tubular portions along middle lines between the sewing lines.
